UNITED STATES PATENT OFFICE.

FRANCIS B. SCOTT, OF BUFFALO, NEW YORK.

IMPROVEMENT IN ROTARY PUMPS.

Specification forming part of Letters Patent No. 36,577, dated September 30, 1862.

To all whom it may concern:

Be it known that I, FRANCIS B. SCOTT, of the city of Buffalo and State of New York, have invented certain new and useful Improvements in Rotary Pumps; and I do hereby declare that the following is a full and exact description of the construction and operation thereof, reference being had to the accompanying drawings, making a part of this specification, in which—

Figure I is a plan of rotary pump having a central discharge. Fig. II is a vertical section of same. Fig. III is a plan of pump with side discharge; Figs. IV and IV^a, details of the forcing-piston as connected to a hinged and radial arm. Figs. V and V^a represent a piston slightly differing in form from the other, showing a spring-packing connected therewith.

Letters of like name and kind refer to like parts in each of the figures.

A represents the case, which is made, of cast-iron or other suitable metal, in two parts, which parts are secured to each other by the bolts *a'* and form the external shell or case. The suction-orifice is shown at B, and the discharge-orifice is shown at C. A cam is cast or placed upon the inside of one of these parts, as shown by the dotted lines D in Fig. I, in which cam a friction-roller works, in order to give the valve or piston its required outward and inward movement to insure its proper action upon the water. This friction-roller is connected to and projects from the piston, as shown at *e*.

F represents the valve or piston cylinder, which is fitted to work within the case and carry the pistons. Its diameter is less than that of the case, the difference being equal (or nearly so) to the throw or outward and inward movement of the pistons. The piston is hinged or jointed to the cylinder, as shown at *g*, so as to allow of an easy outward and inward movement. Slots or openings are made through the cylinder, as shown at *h*, through which the pistons move. These may be "bab-bitted." An abutment is placed just forward of the discharge-orifice within the case and between the suction and discharge orifices, as shown at *i* in Figs. I and III.

J represents the valve or piston, which has the form of an arc, and J' the radial arm which connects it to the cylinder F. It may

be made with a plane square end, as shown in Fig. IV, or with a rounded end, as shown in Fig. V. In either form the piston must exactly fit the water-space within the case.

The case may be packed in a common manner, and the piston may have a spring-packing, as shown at K, Figs. V and V^a.

The piston and radial arm may be made in one casting, or the piston may be made separate from the radial arm and connected thereto by a bolt, screw, or otherwise. In Fig. IV it is shown as connected to the radial arm by a set-screw, *l*. A slot is made in the shank of the piston, as shown at *m*, Fig. IV^a, through which the screw passes and screws into the lug in the radial arm, as shown at *n*, Fig. IV. The object of this slot is to make the piston adjustable, so that if it wears off at the end by rubbing against the case it may be moved up and made to fit water-tight against the case. The piston (as a modification) may also be made tapering, and the inside of the case made tapering to correspond, and then when it is moved up (after wearing enough to get loose) it will insure a water-tight fit at the sides as well as at the end. When made tapering, as described, no packing will be required on the piston.

The shaft P, which connects to and revolves the piston - cylinder, is made hollow, with openings *p'* made through the sides, which open into and take water from the chamber *s*, so that the shaft answers the double purpose of shaft and discharge-pipe. It connects with the short solid shaft *p''*, which has a bearing on the inside of the case, as shown at *p'*.

A water-chamber is made in the case on the outside, as shown at *s*, which conducts the water from the water-space W within the case to the discharge-orifice or hollow shaft.

The form of pump shown in Fig. III, with side discharge, may be advantageously used as a "blower" for blast-furnaces, and with reversed action will make a good rotary steam or gas engine; also, if placed under a head of water will make a powerful water-wheel for mills, &c.

Operation: This pump being constructed substantially as described, power is applied through the crank R, or by steam, in a common manner. The friction-roller *e*, which is connected with each piston, moves in the cam D and throws the pistons outwardly through

the slots in the cylinder at the proper time to carry the water forward to the discharge-pipe, the cam and friction-roller also causing the pistons to draw back into the cylinder at the proper time to pass the abutment.

A pump constructed upon the principle substantially as herein described possesses great strength and durability and may be used not only for pumping clean water, but may also be used for pumping tan liquor and bark, and also as a "wrecking-pump." It possesses so much strength and has so much purchase upon its pistons that plastic bodies—such as clay for tile-making, which needs great pressure for forming into tile—may be run through it to great advantage; and for this purpose a de-

vice for giving form to the tile needs only to be attached to the discharge-orifice of the case, with the necessary apparatus for feeding.

What I claim as my invention, and desire to secure by Letters Patent, is—

1. The arrangement of the piston-cylinder F, pistons J, and cam D, with the case A, substantially as herein set forth.

2. The hollow rotary shaft P, in combination with the water-chamber S, substantially as described.

FRANCIS B. SCOTT.
